UNITED STATES PATENT OFFICE.

WILLIAM BURT, OF PARIS, CANADA.

DESIGN FOR A TRUSS-PAD.

SPECIFICATION forming part of Design No. 30,861, dated May 23, 1899.

Application filed December 29, 1898. Serial No. 700,661. Term of patent 7 years.

To all whom it may concern:

Be it known that I, WILLIAM BURT, a subject of Her Majesty the Queen of Great Britain, residing at the town of Paris, in the county of 5 Brant and Province of Ontario, Canada, have invented and produced a new and original Design for a Truss-Pad, of which the following is a specification, reference being had to the accompanying drawings, forming a part 10 thereof.

Figure 1 is an edgewise view in perspective of the truss-pad. Fig. 2 is a face view of the truss-pad. Fig. 3 is a vertical longitudinal section, and Fig. 4 is a cross-section through 15 the line *a b* of Fig. 3.

In the accompanying drawings, A repre-

sents the truss-pad of the peculiar configuration shown, the leading material feature of which consists in having the smaller portion, as at B, upwardly turned, so that the face of 20 the pad C is made hollow or inwardly curved, as particularly indicated in Figs. 1 and 2.

Having described my invention, what I claim as new, and desire to secure by Letters Patent, is—

The design for a truss-pad, substantially as herein shown and described.

Paris, Canada, December 8, 1898.

WILLIAM BURT.
